(57) **CLAIM**

The ornamental design for an analyte sensor device, as
shown and described.

DESCRIPTION

FIG. 1 is a top perspective view of an analyte sensor device
showing our new design;

FIG. 2 is a top plan view thereof; and,

FIG. 3 is a cross-sectional view taken along the line 3-3 in
FIG. 2.

(Continued)

The dashed broken lines in the figures illustrate portions of the analyte sensor device that form no part of the claimed design.
